UNITED STATES PATENT OFFICE.

WILLIAM B. REIS, OF NEW YORK, N. Y.

CONTROLLING DEVICE FOR DOUBLE DOORS.

No. 835,984.

Specification of Letters Patent.

Patented Nov. 13, 1906.

Application filed August 7, 1906. Serial No. 329,532.

To all whom it may concern:

Be it known that I, WILLIAM B. REIS, a citizen of the United States, and a resident of the city of New York, borough of the Bronx, in the county and State of New York, have invented a new and Improved Controlling Device for Double Doors, of which the following is a full, clear, and exact description.

10 This invention relates to improvements in devices for controlling the movements of double doors, the device being adapted for use particularly in connection with doors of music-cabinets or the like, the object being 15 to provide a simple means whereby companion doors may be swung simultaneously to open position or to closed position by the manual manipulation of one door.

I will describe a controlling device for 20 double doors embodying my invention and then point out the novel features in the appended claim.

Reference is to be had to the accompanying drawings, forming a part of this specification, in which similar characters of reference indicate corresponding parts in both the figures.

Figure 1 is a sectional plan of the lower portion of a cabinet and a door-controlling device embodying my invention, showing the doors closed; and Fig. 2 is a similar plan, but showing the doors open.

Referring to the drawings, 1 designates a cabinet, and 2 a bottom or flooring thereof. 35 The front of the cabinet is provided with two swinging doors 3 4. Secured to the bottom or flooring 2 is a guide rod or rail 5, which is raised somewhat from the bottom or flooring,

and movable on this rod or rail is a slide, here shown as consisting of a sleeve 6, and 40 from this sleeve links 7 8 extend to pivotal connection, respectively, with the doors 3 and 4. As here shown, the forward ends of the links have pivotal connections 9 with lugs 10 attached to the inner sides of the 45 doors.

At the rear or inner end of the rod 5 a stop is provided to be engaged by the slide 6, so as to limit the inward-swinging movement of the doors. As here shown, this stop consists of a collar 11 on the rod; but any other form of stop may be employed.

In the operation by taking hold of one of the doors—say, for instance, the door 3 or a knob thereon—and drawing the same outward the slide 6 will be moved along the rod or rail 5 and the door 4 will be simultaneously swung open. Reverse movement, of course, will cause the doors to swing simultaneously to closed position.

Having thus described my invention, I claim as new and desire to secure by Letters Patent—

The combination with a cabinet and double doors therefor, of a rod arranged along 65 and spaced above the bottom of the cabinet, a slide movable on the rod, link connections between said slide and the doors, and a stop on the rod.

In testimony whereof I have signed my 70 name to this specification in the presence of two subscribing witnesses.

WILLIAM B. REIS.
